(57) **CLAIM**

The ornamental design for a flashlight, as shown and described.

DESCRIPTION

FIG. 1 is a front perspective view showing an exemplary embodiment of my new flashlight design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a reduced scale perspective view showing two exemplary flashlights as in FIGS. 1–8 employed in tandem as mounted back-to-back on the shaft of a tool;

FIG. 10 is a perspective view thereof with the tool removed for clarity;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken line showing of a shaft of a tool in FIG. 9 and the broken line showing of a second flashlight paired with my new flashlight design in FIGS. 9–16 represent environment. All other broken lines represent unclaimed portions of the article. The broken lines form no part of the claimed design.

1 Claim, 6 Drawing Sheets
